(57) **CLAIM**

I claim the ornamental design for an indicating communication and control panel for a medical operating room, as shown and described.

DESCRIPTION

FIG. 1 is a front perspective view of an indicating communication and control panel for a medical operating room showing my new design;

FIG. 2 is a front view thereof;

FIG. 3 is a top view of the panel shown in FIG. 1, with the bottom view being a mirror image of the top view;

FIG. 4 is a left side view of the panel shown in FIG. 1, with the right side view being a mirror image of the left side view;

FIG. 5 is a front perspective view of the panel shown in FIG. 1 with certain design elements in an open position, FIG. 1 showing the same design elements in a closed position;

FIG. 6 is a right side view of the panel shown in FIG. 5, the left side view being a mirror image of the right side view; and,

FIG. 7 is a top view of the panel shown in FIG. 5.

The broken lines in the drawings show environmental structure that forms no part of the claimed design. Portions of the drawings have been lined for color. The push button has been lined for the color red.
